UNITED STATES PATENT OFFICE.

ERIC JOHNSON, OF SEATTLE, WASHINGTON.

LUMBER-PILER.

1,231,027.

Specification of Letters Patent. Patented June 26, 1917.

Application filed August 16, 1915. Serial No. 45,607.

To all whom it may concern:

Be it known that I, ERIC JOHNSON, a citizen of the United States of America, and resident of Seattle, in the county of King 5 and State of Washington, have invented certain new and useful Improvements in Lumber-Pilers, of which the following is a specification.

My invention relates to lumber pilers and 10 consists of certain attachments thereto by which the piler may be automatically supplied with its lumber.

The object of my invention is to provide 15 means for automatically loading the conveying chains with lumber and for transferring the lumber into position for such automatic loading, and consists of the parts and combinations of parts which will be hereinafter particularly defined in the claims.

20 In the accompanying drawings I have shown my invention in the form of construction which is now preferred by me.

Figure 1 is an elevation of a piler having my devices applied thereto, this view being 25 taken from one side edge.

Fig. 2 is an elevation of the same parts taken from in front.

Fig. 3 is a detail showing the construction 30 of the mechanism for operating the trans- scales.

Fig. 4 is a side elevation showing on a larger scale the mechanism whereby the automatic loader is operated by the lumber carrying chain.

35 Fig. 5 is a section taken through one of the standards of the piler just above the mechanism shown in Fig. 4, and

Fig. 6 is a side view of the hooked link by which the automatic loader is operated.

40 The lumber piler herein illustrated is, in its general features, of a form of construction which is now in use. This structure consists of a frame composed of standards 1 with suitable connecting braces, as 10, these 45 standards forming guides for two endless chains, the two standards being separated a sufficient distance to form a bearing of substantial length upon which to carry the lumber. This frame is provided with guide

50 wheels 11 at the top, and 12 at the bottom, over which the chain passes. The chain is provided with lumber carrying fingers or flights 20, which are arranged in pairs. Between the two fingers of each pair, the lumber is placed. These chains are operated

by any suitable means, this not being herein shown.

Two loading arms 4 are provided, one at each side of the frame. These arms are pivoted at some point backward or inside of 60 the frame members 1 and project outwardly or toward the front to a point a sufficient distance beyond the ends of the flights 20 to provide sufficient holding room for the lumber being handled. As a matter of convenience, in reversing these arms, to thereby permit loading from either side of the piler, the pivot point 40 should be located on the central frame of the structure. When so located, the arm may be removed from its 70 pivot, reversed in position and resecured upon its pivot, whereupon it may be used for loading the piler from the other side.

The loading arms 4 are preferably provided with a series of rollers or wheels 42, 75 which project somewhat above the upper edges of the arms, whereby a board, as 45, placed thereon will be moved laterally by inclining the arm 4 only a slight amount. The lumber is placed upon or over the outer 80 end of the arms 4 while the latter are in their lower-most position, which position is indicated by dotted lines in Fig. 1. Means are provided whereby these arms are automatically raised into inclined position, as is 85 shown in Fig. 1, this elevation being timed to correspond with the positions of the passing flights to cause the lumber to be moved inward into the space between the flights of a pair, as is indicated in Fig. 1.

90 The means for elevating the loading arms are as follows: The chains 2 carry a series of members which are shown in plan in Fig. 5, these comprising arms 22, upon the ends of which are journaled rollers 21, which project laterally beyond the edges of the guide channel 1 in which the chain moves. By placing these rollers half way between the flights and by properly proportioning the links 3, by which the bars 4 are raised, they 95 may be shifted to operate alike at either side of the piler.

100 The links 3 are pivoted at 30 to the arms 4. At their upper ends they are each provided with a head 31 which is off-set at one side, 10 said off-set being provided with a downwardly facing surface 33, which is positioned so as to normally be in the path of movement of the tappet rollers 21, carried by the chains. When one of these tappet roll- 110

ers contact with the hook thus formed on the link 3, this link will be raised, carrying with it the loading arms 4. Mounted upon the channel bars 1, which form the main posts 6 of the frame are releasing tappets 13, which engage the inclined or cam-like upper surface 32 of the head of the link 3, to force this link backward and thus free it from the lifting tappets or rollers 21, thus permitting 10 the loading arms 4 to drop. To further insure a positive backward return of the links 3 I provide a roller 34 at the side of the link, and a cam finger 14, with which said roller engages. The descent of the link 3 thus 15 causes the link to be positively moved forward into position to engage the next lifting tappet 21.

Transfer skids 5 are provided, these extending alongside of the loading arms 4 20 and being in some respects of similar construction. These transfer skids are provided with rollers or wheels 51 to facilitate easy movements of the lumber thereover. These transfer skids are also mounted so 25 as to be moved vertically through a slight distance. I have herein shown these skids as pivoted upon the central axis of the frame to thereby facilitate their being used at either side of the loader.

30 Under these conditions it is desirable to operate transfer rollers for the movement of the lumber lengthwise into position alongside of the piler. I have shown three such rollers 6, these being journaled in a frame 35 60, which may be placed in position alongside of the piler. These transfer rolls have their axis extending in the same direction as the transfer skids 5. They are placed at such an elevation that their upper edge is 40 slightly higher than the rollers 51 of the transfer skids, while the latter are in their lowermost position and slightly below the upper edges of the same rollers 51 when the transfer skids are in their uppermost position.

5 It is intended that while the lumber is being moved endwise into position in front of the piler, during which time it will be supported by the transfer rolls 6, that the transfer skids 5 be maintained in their lowermost position. When the lumber has been placed in position alongside of the piler it is transferred to the loading arms 4 by raising the transfer skids 5 enough to raise 5 the piece of lumber 46 off of the transfer rolls 6, whereupon the lumber may be easily moved laterally, being supported upon the rollers or wheels 51.

6 The manner of raising the transfer skids 0 is as follows: The frame 60 has a shaft 7 extending lengthwise thereof and provided with a cam 70 for each transfer skid. A vertical post or bar 8 is provided with two fingers 80 adapted to straddle the shaft 7 5 to thereby permit raising and lowering of

the post 8 while retaining it in alignment with the shaft. The lower end of this post is also provided with two shorter fingers or an equivalent flange 81, which engages the opposite side of the cam 70, thereby maintaining it in position lengthwise of the shaft. By turning the shaft 7 the posts 8 will be raised or lowered carrying with them the transfer skids 5.

An operating lever may be placed directly 75 upon the shaft 7 or an extension thereof. I have, however, shown a transverse shaft 90 upon which an operating lever 9 is placed and have connected the two shafts 7 and 90 by means of bevel gears 72. These gears may be segmental gears only as these shafts will be moved only through a comparatively small angle. The shaft 7 may be provided with arms 71 which extend upwardly in position such that when the shaft is rocked 85 these arms will engage the outer edges of the lumber to move the same inward upon the transfer skids.

At the time of movement of the lumber 90 inward upon the transfer skids, the loading arms 4 would be in their lowermost position. The lumber is thus moved upon the outer end of the loading arms 4, in position for transfer to the flights when the loading arms are raised. To prevent the possibility of 95 lumber being moved inward so as to get behind the raised ends of the loading arms 4 I provide the latter with downward extending fingers 41, of such length that their lower ends never get above the transfer 100 skids. These act as stops to prevent the lumber getting under the loading arms.

To positively insure that the tappet rolls 21, carried by the chain, will not be forced 105 outward by their engagement with the hook surface 33 of the links 3, I provide a member 55 which is secured to the standards or posts 1, these members having webs 59 extending forward at each side of the post and a finger 56 extending downward and forming a channel for engagement with the outer surface of the lifting rolls 21. The side webs 59 are spaced outward from the side edges of the posts 1 a sufficient distance to accommodate the lifting rolls 21, and the retaining fingers 56 project backward or toward the center of the post as is clearly 110 shown in Fig. 5.

The releasing tappets 13 are also mounted 115 upon this member 55, each tappet being carried by a securing bolt which is adjustable vertically in the slot 58 of a downwardly projecting arm 57. By this means the vertical position of the releasing tappet may be 120 adjusted.

The transfer skids 5 are provided with 125 upwardly projecting stops 52 which are located just outside the line of travel of the outer ends of the flights 20, which act to prevent lumber being moved far enough to 130

be engaged by the flights prior to its insertion therein by the loading arms.

Having thus described my invention, what I claim as new, and desire to secure by Letters Patent of the United States of America, is:—

1. In a lumber piler, in combination, endless chains having lumber carrying flights, top and bottom guides for said chains, means for actuating the chains, loading arms pivoted backward of the chains, and extending outwardly of the flights a distance to receive the lumber thereon, and means for raising said arm actuated by the chains at the passage of each set of flights.

2. In a lumber piler, in combination, endless chains having lumber carrying flights, top and bottom guides for said chains, means for actuating the chains, loading arms pivoted backward of the chains, and extending outwardly of the flights a distance to receive the lumber thereon, a hook arm connected with each loading arm adjacent the chain, and tappets carried by the chains to engage said hook to lift the loading arm at the passage of each set of flights.

3. In a lumber piler, in combination, endless chains having lumber carrying fingers thereon, top and bottom guides for said chains, means for actuating the chains, transfer bars adapted to receive the lumber, loading bars adapted to receive the lumber from the transfer bars, lifting tappets carried by the chain for each set of carrying fingers, a member connected with the lifting bars and adapted to be actuated by engagement with said tappets, and fixed releasing tappets positioned to engage said lifting member to release it from the lifting tappets.

4. In a lumber piler, in combination, endless chains having lumber carrying fingers thereon, top and bottom guides for said chains, means for actuating the chains, transfer bars adapted to receive the lumber, loading bars adapted to receive the lumber from the transfer bars, a link pivoted to each lifting bar and extending alongside the chains, the upper ends of said links being provided with a downwardly facing surface, lifting tappets carried by the chains for each set of carrying fingers and adapted to engage said downwardly facing surface of the links, and cam-like members controlling said links to release them and bring them back into engaging position.

5. In a lumber piler, the combination with the lumber elevating mechanism, of loading arms pivoted at the back side of the elevating mechanism and projecting forwardly thereof, lumber supporting wheels carried by the part of the loading arms which extend beyond the chains, and means for intermittently lifting the loading arms by the elevating mechanism to transfer the lumber to the latter.

6. In a lumber piler, in combination, an endless chain carrying lumber carrying flights, top and bottom supporting and driving guides therefor, loading bars pivoted centrally of the runs of said chain at the lower end thereof and extending forwardly of the flights of the rising run, transferring skids extending in the same direction and projecting beyond the loading arms, means for automatically raising the loading arms upon the passage of the carrying flights, and means for transferring lumber from the transfer skids to the loading arms.

7. In a lumber piler, the combination with the lumber elevating mechanism having lumber carrying flights, of loading arms pivoted at the back side of the elevating mechanism and projecting forwardly thereof, wheels carried by that part of the loading arms extending beyond the elevating members and supporting the lumber placed thereon, stops independent of the loading arms and outside of the path of movement of the flights and limiting the movement of the lumber upon the loading arms, and means for intermittently lifting the loading arms by the elevating mechanism to transfer the lumber to the flights thereof.

8. In a lumber piler, a lumber elevating mechanism having lumber supporting fingers, loading arms adjacent and extending across the path of movement of said fingers and pivoted at the opposite side of the elevating mechanism from their loading ends, and means intermittently connecting said loading arms with the lumber elevating mechanism, whereby the loading ends of said arms are given a bodily movement with the said fingers and a tilting movement toward said fingers.

9. In a lumber piler, in combination, an elevating chain having lumber carrying flights thereon, a tiltable loading arm extending outwardly from said chain, the chain having tappet members, and a catch member connected with the loading arm to engage said tappet to raise the loading arm, the catch member having a cam surface, and a member fixed to engage said cam surface to release the catch member at a predetermined point.

10. In a lumber piler, in combination, an elevating chain having lumber carrying flights thereon, a tiltable loading arm extending outwardly from said chain, a projecting member carried by the chain for each set of flights thereof, a link connected with the loading arm and having a tooth surface engaged by said projecting members to raise the loading arm, and an adjustably fixed member adapted to engage the link to disengage it from said projecting member.

11. In a lumber piler, in combination, an elevating chain having lumber carrying flights thereon, a tiltable loading arm ex-

- tending outwardly from said chain, a projecting member carried by the chain for each set of flights thereof, a link connected with the loading arm and having a tooth 5 surface normally placed in the path of said projecting members and an inclined surface above said tooth, and a disengaging stop positioned to engage said inclined surface to release said link at a predetermined point.
- 10 12. In a lumber piler, in combination, an elevating chain and lumber carrying flights carried thereon, a loading arm pivoted rearwardly of the chain and extending forwardly of the flights, a link pivoted to the 15 loading arm adjacent the chain and having a downwardly facing tooth, a disengaging surface inclined to the direction of movement of the chain and a side projecting member, the chain carrying a series of laterally projecting members positioned alike relative each to its particular flight and to 20 engage the tooth of said link to raise it, a disengaging wiper positioned to engage the inclined disengaging surface of the link, and a fixed member having a cam surface engaging the side projecting member of the link to throw the link into engaging position when it drops. 25
13. In a lumber piler, in combination, a frame, an endless chain having lumber carrying flights and a lifting tappet for each set of flights, a pivoted loading arm extending outward of the flights, a link pivoted to the loading arm and having a tooth surface normally positioned to engage the lifting 30 tappets, a third finger carried by the frame in position to be engaged by the lifting tappets while engaged with said link, and means for disengaging said link at a predetermined point. 35
- Signed at Seattle, Washington, this 10th day of August, 1915.

ERIC JOHNSON.
